UNITED STATES PATENT OFFICE

2,435,023

HEATING MEANS FOR CENTRIFUGAL
BASKETS

Pieter van Riel, Delft, Netherlands, assignor to
Machinefabriek Reineveld N. V., Delft, Netherlands, a company of the Netherlands

Application November 21, 1945. Serial No. 630,078
In the Netherlands July 30, 1940

Section 1, Public Law 690, August 8, 1946
Patent expires July 30, 1960

4 Claims. (Cl. 210—66)

1

This invention relates to a centrifugal machine of the type wherein the wall of the drum is provided with a passage, or with passages, through which a heating or a cooling liquid is adapted to flow under the action of the centrifugal force.

In a known machine of this type the liquid, which is supplied to the jacketed bottom of the drum, is thrown outwards immediately after reaching the top edge of the drum, so that only a small part of its heat can be exchanged against that of the charge under treatment.

The invention has for its purpose to render the rate, at which the liquid flows through said passages, controllable and to allow the liquid still present therein after the charge has been subjected to centrifugal treatment during the required time, to be discharged as the speed of the drum decreases. In accordance with the invention, the drum is provided with a jacketed bottom and with a jacketed top, both communicating with the passages and both extending inward to a suitable distance from the axis, a stationary supply and skimming pipe being provided so as to open into the bottom jacket.

The more or less diagrammatic drawing illustrates, by way of example only, a centrifugal machine in accordance with the invention, Fig. 1 being a vertical sectional elevation, and Fig. 2 a fragmentary section on the line II—II in Fig. 1.

The material to be treated is supplied through a pipe 3 centrally into the drum or bowl 4. The peripheral wall of the drum is formed by a circular series of axially disposed and suitably spaced straight pipes 5, interconnected by perforated webs 6, the smooth inner face of said wall being lined by wire gauze 7.

The drum has a jacketed bottom 8 communicating with the lower ends of the pipes 5. Opening into said jacket is a stationary pipe 9, whose mouth extends radially outwards and which is connected, through a three-way cock 10, to a pipe 11 for supplying, and to a pipe 12 for discharging a heating or a cooling liquid. Provided in said jacket are radial partitions 13 intermediate the bottom openings of the pipes 5.

At their tops, the pipes 5 communicate with an annular, jacketed top 14, which communicates, along its inner edge, with an annular chamber 15 provided with a discharge nozzle 16.

The described centrifuge operates as follows.

Let it be assumed that the drum 4 is driven at a suitable speed and charged with material that is to be kept at a predetermined temperature, and that a heating liquid is supplied to the jack-

2

eted bottom 8 by way of the pipes 11 and 9. Owing to centrifugal action, said liquid is thrown outward into the pipes 5 and forced to rise therein so as to enter the jacketed top 14, whence it is discharged, through the chamber 15, by the nozzle 16. By using a liquid of suitable temperature and controlling, by means of the cock 10, the rate at which the liquid circulates through the system 8, 5, 14, it is possible to keep the charge 10 at the desired temperature during its centrifugal treatment in the machine.

After the treatment, the cock 10 is set to establish communication between the pipes 9 and 12 and the speed of the drum 4 is reduced, so that 15 the liquid still present in pipes 5 is allowed to gradually sink and be skimmed off by the pipe 9.

What I claim is:

1. In a centrifugal machine, a drum having a passage in the peripheral wall thereof, a jacketed 20 top on said drum and a jacketed bottom on said drum, the said jacketed portions of said drum extending inwardly and having openings therein communicating with said passage in said wall, means for introducing a fluid to said jacketed 25 portions and said passage, and a skimming and discharge pipe introduced in said jacketed bottom whereby said liquid may be removed from said bottom.

2. In a centrifugal machine, a drum having 30 a passage in the peripheral wall thereof, a top member on said drum having spaced portions thereof defining a compartment, a bottom member on said drum having spaced portions thereof defining a compartment said compartments 35 extending inwardly and having openings therein communicating with said passage in said wall, means for introducing a fluid to said compartments and said passage, and a skimming and discharge pipe entering said bottom compartment 40 whereby said liquid may be removed from said compartment.

3. In a centrifugal machine as claimed in claim 2, the said peripheral wall of said drum comprising a circular series of axially disposed pipes 45 interconnected by perforated webs and the inner face of said wall having a wire gauze lining, said pipes having openings in the ends thereof communicating with said openings in said top and bottom compartments, the said bottom compartment 50 having radial partitions intermediate said openings in said axially disposed pipes thereby forming a passage for said fluid.

4. In a centrifugal machine as claimed in claim 2, the said fluid introducing means comprising a stationary injector inserted in said bottom com-

partment and having a radial outward extending portion with an opening therein and a control valve connected to said injector whereby the rate of flow of said liquid through said injector and said passage in said drum may be controlled.

PIETER VAN RIEL.
